APPARATUS FOR REMOVING COLLAPSIBLE
TUBES FROM THE EXTRUDING PLUNGERS
OF EXTRUDING MACHINES

Frederic Remington, Elizabeth, and Richard A. Tartaglia, East Orange, N. J., assignors to Peerless Tube Company, Bloomfield, N. J., a corporation of New Jersey

Application May 10, 1950, Serial No. 161,214

4 Claims. (Cl. 207—6)

1

This invention relates in general to the manufacture of collapsible tubes that are commonly used for packaging tooth paste, toilet creams, paints, glue and other products.

This application is a continuation-in-part of our co-pending application Serial No. 115,378 filed September 13, 1949, and is related to our application Serial No. 80,162 filed March 8, 1949, and now Patent No. 2,600,921.

In the manufacture of such collapsible tubes, a slug of metal is placed in a die, for example on the bed of a power press, and a plunger, carried by a reciprocating head in the press, is forced into the die under high pressure so as to cause the metal to flow back along the plunger, thereby to produce a tube having a cylindrical body portion of irregular length, a sloping shoulder and a neck closed by a web at the end. It is necessary to remove or strip the collapsible tube from the plunger, and generally the stroke of the head of the press is of sufficient length to permit the plunger to be withdrawn a distance from the die greater than the length of the collapsible tube so as to permit the tube to be stripped or pushed from the end of the plunger. However, considerable waste of power and time is involved in such long strokes of the head of the press, and in our aforesaid copending applications there are described power presses which include constructions such that the stroke of the press head may be substantially less than the length of the collapsible tube and yet the tube can be easily, quickly and automatically removed from the plunger, whereby collapsible tubes can be rapidly produced with a minimum of power.

More particularly the invention is intended for use in connection with a collapsible tube extruding machine of that type and includes a frame having a die cavity thereon to receive a slug of metal, a plunger mounted on a vertically reciprocable press head in said frame and reciprocable into and out of said cavity to extrude said slug in the plunger and withdraw said tube from the cavity respectively, said plunger being swingable bodily from a first position out of the die cavity and at one side of the die into a second position in vertical axial alignment with the die cavity and from said second position into the first position while the plunger is out of said die cavity; and another object of the invention is to provide novel and improved means for stripping or removing the collapsible tube from said plunger during movement of the plunger from the second position into the first position.

Still another object is to provide such means

2

for stripping or removing the collapsible tube from the plunger which shall include a stripping head slidable longitudinally of the plunger, and novel means mounted on said frame and operated by said press head for actuating said stripping head.

Other objects, advantages and results of the invention will be brought out by the following description in conjunction with the accompanying drawings in which

Figure 1 is a schematic front elevational view of a machine for extruding collapsible tubes embodying the invention, showing the extruding plunger in said second or tube extruding position and with portions broken away and shown in section;

Figure 2 is a vertical sectional view approximately on the plane of the line 2—2 of Figure 1;

Figure 3 is a view similar to Figure 2 showing the extruding plunger in its first or tube stripping position;

Figure 4 is a horizontal sectional view approximately on the plane of the line 4—4 of Figure 2;

Figure 5 is a fragmentary side elevational view of the extruding die with portions broken away to show a slug of metal in the die cavity, and

Figure 6 is a fragmentary side elevational view of the die and a portion of the extruding plunger, illustrating the tube extruding operation.

For the purpose of illustrating the principles of the invention we have shown it in conjunction with a generally known type of power press portions of which have been omitted because they have no bearing on the invention. More particularly, the press includes a bed A at opposite sides of which are vertical side pieces B in each of which is a vertical slide way C opposed to the slide way of the other side piece for guiding the vertical reciprocation of the head D of the press which is reciprocated by any suitable power driven mechanism (not shown).

On the bed of the press is mounted a die E in which is a cylindrical die cavity 1 that has an inverted frusto-conical bottom wall 2 at the smaller end of which is a coaxial recess or opening 3.

Cooperative with the die is a plunger 4 having a frusto-conical end 5 and a coaxial mandrel projection 6, the plunger 4 being of a diameter less than the diameter of the die cavity and the mandrel projection 6 being of a diameter less than the recess 3.

With this construction, when a slug 7 of metal of a volume to give a collapsible tube of the desired size and weight is placed in the die cavity,

as shown in Figure 5, and the plunger 4 is forced downwardly into the cavity against the slug 7, the metal of the latter is caused to flow, first tending to fill the die cavity and then flow backwardly or upwardly along the exterior surface of the plunger to form the tubular body 8 of a collapsible tube F as shown in Figure 6. As the plunger completes its downward stroke, the sloping shoulder 9 and the closed neck 10 of the collapsible tube are formed between the juxtaposed surfaces of the plunger and die.

The invention is shown in combination with means identical with that shown in our co-pending application, Serial No. 80,162, filed March 8, 1949, and now Patent No. 2,600,921, for automatically manipulating the plunger so that the tube can be removed therefrom upon an upward movement of the plunger a distance substantially less than the length of the tube. As shown the plunger is rigidly connected at one end to a head block 11 which in turn is pivotally connected at 12 to the bottom side of the head D of the press to swing in an axis at one side of and perpendicular to the longitudinal axis of the plunger, so that the head block may be swung into abutting contact with the bottom surface of the head D so as to locate the plunger above and coaxial with the die cavity 1, or the block may be swung downwardly away from the bottom surface of the press head so as to move the plunger laterally away from the die E into an inclined position as shown in Figure 3 of the drawings to permit the collapsible tube to slide downwardly off the plunger. As shown, the bottom surface of the press head is flat and perpendicular to the direction of reciprocation of the head, and the upper surface of the head block 11 is also flat, so that when the head block is swung to bring its upper surface into contact with the bottom surface of the press head, the plunger 4 will be locked or held against tilting during the extruding operation.

Means is also provided for oscillating the head block and plunger from one of said positions to the other, and as shown, said means comprises a bifurcated arm 13 on the head block 11 which is pivotally connected at 14 to one end of a link 15 the other end of which is pivotally connected at 16 to one end of a crank arm 17 which is rigidly connected to a shaft 18 journaled to swing about a horizontal axis in bearing lugs 19 on the press head. A second crank arm 20 is also rigidly connected to the shaft 18 and extends therefrom in a direction opposite to that of the crank arm 17, and the crank arm 20 has a follower roller 21 movable in a cam groove 22 formed in a block 23 that is secured to one of the side pieces B of the press. The cam groove 22 has two horizontally offset vertical portions 22a and 22b between which is a curved portion 22c, said portions being so related and in such relation to the movement of the press head, that when the press head is in its upper normal position as shown in Figure 3, the roller 21 is in the upper portion of the groove 22 to hold the die block and plunger in the tube-discharging position, while at the beginning of the descent of the press head, the roller 21 moves through the curved portion 22c of the groove and into the lower straight portion 22b so as to swing and hold the head block 11 in contact with the bottom surface of the press head and with the plunger 4 coaxial with the die cavity.

In operation of the apparatus, the parts are initially in the position shown in Figure 3, and a slug 7 is dropped into the die cavity 1 by any suit-

able feeding mechanism, preferably in timed relation to the reciprocation of the press head D. After the slug has been so disposed, the press head begins its descent and the plunger is swung into axial alinement with the die cavity; continued descent of the press head causes the plunger to be forced into the die cavity as shown in Figures 1, 2, 4 and 6. Upon the ascent of the press head, the plunger is first removed from the die cavity 1 and then is automatically swung into its offset inclined position with its free end at one side of the die as shown by solid lines in Figure 3. Thereupon the tube is slid off the plunger as indicated by dot and dash lines in Figure 3 by the stripping means embodying the invention. This means is shown as comprising a stripping head G which is movable longitudinally of the plunger 4 and is mounted at one end of a bracket arm 24 the other end of which is rigidly connected to a tubular slide 25 which is slidably reciprocable on a guide rod 26, that is rigidly mounted on the block 11 in spaced and parallel relation to the plunger 4. The stripping head is slideable on the plunger 4 to abut the open or upper end of a tube F so as to push the tube off the plunger during downward movement of the stripping head on the plunger.

Means for reciprocating the tubular slide 25 comprises a fork 27 which embraces the slide and has its arms pivotally connected thereto as indicated at 28, said fork having a shank 29, the end of which opposite the fork is slidably mounted in a socket 30 formed in an arm on a rocker bar 31 which is journaled at its ends in the side pieces B of the press frame as indicated at 32, so as to oscillate about a horizontal axis. A pair of spaced arms 33 project from the rear of the rocker bar at the side of its pivots 32 opposite the fork and are pivotally connected to one end of a link 34, the other end of which passes through a slot 35 in an arm 36 which projects rigidly from the press head D, nuts and a collar or washer 37 being secured on the link 34 above said arm 36 so that upon upward movement of the press head, the link will be pulled upwardly to swing the rocker bar 31 and move the fork 27 and slide 25 downwardly. The rocker bar is swung in the other direction by tension springs 38 that are connected by pins 39 on the rocker bar to lugs 40 on the bed of the press.

In operation of the stripping mechanism and assuming the plunger 4 to be in the tube extruding position shown in Figure 1, the first portion of the upward movement of the press head withdraws the plunger and tube from the die cavity, whereupon the roller 21 engages the cam surfaces 22c and 22a so as to swing the plunger 4 outwardly or forwardly away from the die as shown in Figure 3. Then, continued upward movement of the press head will cause actuation of the rocker bar 31 to force the slide 25 and the stripping head downwardly until the collapsible tube has been pushed completely off the plunger, as shown in Figure 3, the shank 29 of the fork sliding outwardly in the socket 30 to compensate for the outward swinging movement of the plunger 25. Upon the beginning of the descent of the press head, the rocker bar 31 will be actuated to raise the stripping head G and the roller 21 will move into engagement with the cam surfaces 22b so as to return the plunger into alinement with the die cavity in readiness for the next extruding operation as shown in Figures 1 and 2, the shank 29 sliding inwardly of the socket 30

as the plunger 26 moves to the extruding position.

As will be understood by those skilled in the art, the discharged tubes may be handled in any suitable manner; for example, they may be dropped upon an endless conveyor by which they may be transported to a point for the next operation upon the tube such as the trimming of the open end of the tube or the threading of the neck, etc.

As usual in the manufacture of collapsible tubes, the press head D will be rapidly reciprocated and automatically controlled by mechanism well known in the art, and the slugs 7 will be fed to the die cavity in timed relation to the reciprocation of the press head by means equally well known. The reciprocating stroke of the plunger is only long enough to produce the required displacement of the metal of the slug and to clear the free end of the plunger with the tube thereon from the top of the die, and therefore collapsible tubes can be produced rapidly with a minimum of power. It will also be observed that the stripping mechanism effectually compensates for the swinging movement of the extruding plunger and yet is simple and inexpensive in construction and economically actuated by the press head.

It will be understood by those skilled in the art that the now preferred form of the invention has been illustrated for the purpose of illustrating the principles of the invention but that many modifications and changes may be made in the details and construction of the machine within the spirit and scope of the invention.

We claim:

1. A machine for extruding tubes, comprising a frame, a die mounted thereon and having a die cavity, a head vertically reciprocable on said frame, an extruding plunger carried by said head, and means for bodily swinging said plunger into and out of axial alignment with said die cavity upon reciprocation of said head, a stripper slide longitudinally of said plunger to engage the open end of a tube formed on said plunger, and means for sliding said stripper in opposite directions upon reciprocation of said head including a rigid vertical shaft on said head parallel to said plunger, a slide reciprocable on said shaft and connected to said stripper, a rocker bar mounted on said frame to oscillate on a fixed horizontal axis, means connecting said rocker bar to said slide including relatively movable parts to accommodate said oscillation of said rocker bar and the swinging of said plunger and linear movement of said slide, and means including a

connection between said rocker bar and said head to oscillate said rocker bar upon reciprocation of said head.

2. A machine for extruding tubes, comprising a frame, a die mounted thereon and having a die cavity, a head vertically reciprocable on said frame, an extruding plunger carried by said head, and means for bodily swinging said plunger into and out of axial alignment with said die cavity during downward and upward movement of said head respectively, a stripper slide longitudinally of said plunger, and means for sliding said stripper in opposite directions upon reciprocation of said head, including a slide connected to said stripper, means mounting said slide on said head to vertically reciprocate relatively to and with said head, a rocker bar mounted on said frame to oscillate on a fixed horizontal axis, means connecting said rocker bar to said slide including parts, at least one of which is connected to and movable with said slide during swinging of said plunger, at least another part connected to and oscillatable with said rocker bar and means connecting said parts for movement relatively to each other to accommodate said oscillation of said rocker bar and the swinging of said plunger, and means including a connection between said rocker bar and said head to oscillate said rocker bar upon reciprocation of said head.

3. A machine for extruding tubes as defined in claim 1 wherein said connection between said rocker bar and said head includes an arm on said rocker bar, an arm on said head and linkage connected at its opposite ends to said arm on the rocker bar and to said arm on said head respectively.

4. A machine for extruding tubes as defined in claim 1 wherein said connection between said rocker bar and said head includes an arm on said rocker bar, an arm rigidly mounted on said head and having a slot therein, and a link pivotally connected to said arm on the rocker bar and passing through said slot in said arm on the head, said link having an adjustable collar thereon above and to be abutted by said arm on the head as the head moves upwardly.

FREDERIC REMINGTON.
RICHARD A. TARTAGLIA.
